UNITED STATES PATENT OFFICE.

EDMON B. WELCH, JR., OF MUSSELFORK, MISSOURI.

HOE.

1,259,944.

Specification of Letters Patent.

Patented Mar. 19, 1918.

Application filed October 24, 1916. Serial No. 127,430.

To all whom it may concern:

Be it known that I, EDMON B. WELCH, Jr., a citizen of the United States, residing at Musselfork, in the county of Chariton and State of Missouri, have invented certain new and useful Improvements in Hoes, of which the following is a specification.

This invention relates to an improvement in hoes and more particularly to hand implements of this nature such as are particularly adapted for use in weeding or in cultivating the surface of the soil.

An object of my invention is to provide a hoe which has the blade thereof so arranged that it may be moved through the earth in a plane substantially parallel with the surface of the ground, thus allowing all weeds or other foul growth to be felled without the effort usually required in the manipulation of the standard forms of hoes.

A further object is to provide a blade which is substantially rectangular or of other desired shape sharpened around its entire peripheral edge and so mounted in conjunction with the handle that it may be readily removed for sharpening and re-adjusted to present a new cutting edge at the point which is receiving the greatest wear in the use of the implement.

Yet another object lies in so constructing the blade and the fastening means therefor that when the blade is adjusted to a fitted position with respect to the handle, this adjustment will be maintained until the fastening means has been again released.

With the above and other objects in view, my invention consists in certain novel features of construction and combinations of parts which will be hereinafter set forth in connection with the drawings and then more particularly pointed out in the claims.

In the drawings:—

Figure 1 is a view in perspective of the head of a hoe constructed after the manner of my invention,

Fig. 2 is a transverse vertical sectional view through this head structure, and

Fig. 3 is a fragmentary perspective view to better illustrate the manner of constructing the blade.

As is here illustrated, the blade is made substantially square or rectangular in plan, although it will be understood that this blade might be circular, triangular, or of any other desired shape which will best accomplish the action desired in use. The blade

1 is constructed of a thin sheet of metal which is sharpened at its edge to give the proper cutting action in the use of the hoe, and in the present instance this sharpening 60 is accomplished by beveling the top surface of the blade at the edge as indicated at 2 so that the lower side of the blade is left substantially flat throughout its entire extent, this top beveling of the blade presenting the construction in such form that as the hoe is worked through the ground the beveled edge 2 will act to hold the blade in the proper working position where the tendency might be for the blade to ride out of the 70 loose top soil if the blade be beveled on its lower face, to form the cutting edge. The central portion of the blade, where the same is to be secured with the handle, is cut through and is expanded upwardly as better 75 illustrated in Fig. 3 so that a polygonal shaped opening is provided at 3 with the metal which is spread out or folded back to form this opening extending in a rim-like flange 4 therearound.

The handle 5 which is preferably made of the standard form and construction has a shank 6 secured in the end thereof, and this shank is preferably given a slight curve downwardly and then terminates in a 85 widened out socket portion 7 which is preferably made flat on its upper and lower faces. This socket portion 7 has a circular opening through the upper side thereof as indicated at 8, and a polygonally shaped socket 90 9 is provided on the lower side in line with this circular opening 8 and shaped to conform to the shape of the rim-like extension flange 4 of the blade 1. A clamp bolt 10 has the head-end of the shank made of polygonal form as indicated at 11 to fit the opening 3 of the blade 1 and the head 12 of this bolt is preferably widened out gradually from the polygonally shaped portion 11 of the shank and at its top is flat so that as the 95 blade is fitted to the handle by having the rim-like flange 4 fitted in the socket opening 9 of the socket portion or head of the handle shank 6, and the clamp bolt 10 is fitted through the openings 3 and 8, the head 12

100 will present the flat surface thereof in line with the flat lower face of the blade 1. The shank of the bolt 10 is screw-threaded and a clamp nut 13 is screwed upon this threaded end of the bolt to bear against the upper 110 side of the socket portion 7 and thus the clamp bolt will be drawn tightly in against

the blade 3 while this blade will be secured in its fitted mounting in the socket 9 and thus the blade will be held rigidly in conjunction with the handle in angular disposition with respect of the longitudinal extent of the handle and will at the same time be prevented from shifting in its angular disposition or from twisting around the clamp bolt.

10 From the foregoing it will be seen that I have provided a hoe which is so constructed that it may be used with facility and efficiency to work over the top soil in removing weeds therefrom as a "scouring" action is accomplished and that the implement might be used just as effectively in working over the surfaces of gravel paths or drives, and in still other connections.

20 While in the foregoing I have illustrated and described only one form of the device, it will be understood that changes and modifications might be resorted to in the form and arrangement of the various parts without departing from the spirit and scope of my invention, and hence I do not wish to be limited to the exact disclosure but only to such points as may be set forth in the claims.

I claim:—

30 1. A hoe comprising a handle having a shank extended therefrom and terminating in a socket portion having a polygonally shaped opening, a blade having an opening 35 through the body thereof and a rim-like flange shaped to be received in and to fit the opening of the socket portion, and a clamp bolt fitted through the openings of the blade and the socket portion to secure the blade in rigid mounting upon the shank.

2. A hoe comprising a handle, a shank 40 fitted to said handle and terminating in a socket portion, said socket portion provided with a polygonally shaped opening, a blade having a plurality of cutting edges cut and expanded in its central portion to 45 provide an opening therethrough surrounded by a rim-like flange shaped to be received in and fit the opening of the socket portion, and a clamp bolt shaped to fit the opening of the blade and through the socket portion and secured in place to rigidly mount the blade in predetermined position in conjunction with the shank.

3. A hoe comprising a handle, a shank fitted to said handle and provided with a 55 socket portion having a polygonally shaped opening therein, a sheet metal blade provided with a plurality of cutting edges cut through and expanded in its central portion to provide an opening with a rim-like 60 flange upstanding therearound and shaped to fit the opening, a clamp bolt shaped to be received through the opening of the blade and through the socket portion to present the top of the head thereof in the same 65 plane with the lower face of the blade of the hoe, and a lock nut removably fitted upon the clamp bolt to rigidly secure the parts in the operative relation and to permit adjustment of the blade to present the 70 various cutting edges thereof in operative relations.

In testimony whereof I affix my signature in presence of two witnesses.

EDMON B. WELCH, JR.
